ELECTRIC FENCE

Ellsworth D. Willis, Lansing, Mich.

Application December 19, 1938, Serial No. 246,595

6 Claims. (Cl. 256—10)

This invention relates to electric fences, and more particularly to a means for automatically regulating and limiting the current which flows therein.

Electric fences, or in other words, fences of the type which are electrically charged in order to deliver a shock to an animal coming in contact therewith, are well known. Previous to this invention there has been no way for maintaining a continuous current in such a fence which is safe, and at the same time capable of delivering a shock of sufficient magnitude to keep all sorts of animals away from the fence. Most electric fences have employed means for intermittently making and breaking the circuit so as to shock an animal touching the fence but thereafter provide a short interval in which to break away from the fence.

It is well known that animals of different kinds have different internal resistances, and the internal resistance of the same animal may vary from time to time. Also, the resistance in the circuit due to a good or a poor contact of the animal with the fence or ground may vary widely. Because of these wide variations in resistance previous electric fences have been unsatisfactory because if they are provided with sufficient resistance to render them safe at all times, the shock which is delivered to an animal of relatively high resistance will be so slight as to be unnoticeable. On the other hand, if the resistance of the circuit is low enough so that the current is high enough to deliver a shock to an animal of relatively high internal resistance, then the effect on an animal of low resistance may be such as to stun or even kill the animal.

It is an object of this invention, therefore, to provide a circuit for an electric fence which is so arranged that a continuous current will flow therein whenever an animal touches the fence, but this current will be limited to a value that can never become dangerous, no matter what the animal's resistance may be. Another object is to provide an electric fence having an automatically variable compensating impedance for regulating the flow of current. Still another object is to provide a fence having means for delivering current thereto including a thermionic electric discharge device. Another object is to prolong the life of the thermionic device by employing a circuit which is normally open, and which is closed only when some foreign object touches the fence. Still another object of the invention is the provision of means for indicat-

ing when the circuit is closed and current is flowing in the fence.

These objects are attained by means of a novel apparatus for charging the fence including a thermionic device, preferably a conventional vacuum tube of the screen grid type, inserted in series in the circuit whereby the current flowing in the circuit must traverse the space in the tube between the cathode and the anode thereof. The current is automatically controlled by the variation in potential of a control electrode, or grid, to compensate for variations in the external resistance of the entire circuit.

In the drawing the single figure is a wiring diagram, using conventional symbols, which shows the invention embodied in an electric fence having a single bare fence wire supported on insulating posts.

Referring now in more detail to the drawing, the numeral 10 indicates the primary coil of a transformer which is connected to a suitable source of electric current, usually the standard 110 volt 60 cycle household supply. The secondary of the transformer is divided into two coils 11 and 12. Coil 11 has sufficient turns to supply a voltage of approximately 300 volts across the coil when the primary voltage is 110 volts. The coil 12 has sufficient turns to deliver approximately 6.3 volts, and is connected directly to the cathode heater filament 13 of a thermionic vacuum tube 14. The tube 14 is a conventional radio tube of the screen grid type. It has an anode 15, a grid 16, a cathode 18, and a screen grid 17. One terminal of the secondary coil 11 of the transformer is connected to the anode 15 and the other terminal of the secondary coil is connected to the ground 19.

The cathode 18 of the tube 14 is connected through a resistance 20, preferably having a resistance value of 1000 ohms, to a single bare wire 21 which constitutes the electrically charged portion of the fence. This wire 21 is supported on posts 24 set in the ground and is insulated therefrom by suitable insulators 25. The grid 16 is connected to the cathode 18, but with the resistance 20 intermediate the cathode and grid. The anode 15 is connected to the screen grid 17 and this connection is provided with a suitable resistance in order to impress a positive potential on the screen grid. In the particular embodiment disclosed herein this resistance consists of a neon lamp 22 which is so connected that when the circuit is closed this neon lamp will glow and indicate that some object is in contact with the fence and is touching the

ground. In place of the neon lamp any suitable resistance may be used, but of course, a simple resistance will not have the dual function of acting as a resistance and indicating the operation of the electric circuit.

A small condenser 23, preferably of 1 microfarad capacity, is connected to the ground wire and the cathode 18. The current delivered to the fence is rectified A. C., and the maximum effective voltage at the fence, without a condenser, is approximately 150 volts when the voltage at the terminals of the secondary coil 11 is 300 volts. The condenser 23 acts as a filter condenser and raises the maximum effective voltage to approximately 350 volts.

The values of resistance, impedance and capacity of the various elements of the circuit are preferably chosen so that the maximum current which can flow in the circuit when the fence is short circuited by a connection having a negligible resistance is approximately 15 milliamperes. This current is insufficient to be dangerous to any animal which may come in contact with the fence.

The operation of a vacuum tube of the type shown in this circuit is well known, and it is therefore believed to be unnecessary to go into its operation in detail. The operation of the entire circuit is as follows: with the switch in the line circuit closed the primary coil 10 of the transformer will be energized and will induce currents in the secondary coils 11 and 12. Since the circuit including the secondary coil 12 and the heater 13 for the cathode is closed, the heater will be incandescent and will heat the cathode 18. The circuit, including the secondary coil 11, the tube 14 and the fence is open until some foreign object, such as an animal, comes in contact with the fence. When the circuit is closed by any conductor placed between the fence and ground, a current will flow therein, crossing the space between the anode 15 and the cathode 18 of the tube 14. The maximum current which flows in the circuit is limited by the impedance of the tube 14, which cannot pass more than a certain amount of current, and this maximum flow occurs when the fence and ground are connected by a conductor having a negligible resistance. The maximum flow of current in the circuit illustrated is, as stated above, approximately 15 milliamperes.

When the circuit is closed by a conductor, current flows across the space between the anode and cathode of the tube and through the two grids 16 and 17. The grid 16 is at a negative potential relative to the cathode because of the drop in potential across the resistance 20. Therefore, the grid opposes the flow of current to a certain extent and limits it to the value stated.

Now, if an animal having a high resistance closes the circuit instead of the aforementioned conductor having no resistance, the current tends to drop. However, this causes a decrease in the I. R. drop across resistance 20, the grid 16 thereby becomes less negative, and the current flows more freely across the space in the tube. Thus, the increase in resistance of the circuit due to the animal is substantially compensated for by the decreased impedance of the tube 14. No matter what the resistance closing the circuit happens to be, it is automatically compensated for by the change in impedance of the tube.

This circuit does not hold the current exactly constant for all values of the circuit resistance. However, it does regulate it within relatively close limits, of which the maximum current is safe to animal life, while the minimum current is capable

of delivering a strong shock. With the circuit illustrated the current will vary between approximately 7 and 15 milliamperes where the resistance across the fence varies between 30,000 and 0 ohms respectively.

As stated above, the neon lamp acts as the necessary resistance to maintain the screen grid 17 at a positive potential less than that of the anode. At the same time the neon lamp is not illuminated unless the circuit is closed, and therefore, the fact that the lamp glows indicates to the owner of the fence that some foreign object is in contact therewith. It will, of course, be obvious that instead of the neon lamp any suitable resistance may be substituted therefor. However, a simple resistance would not indicate the closed or opened condition of the circuit.

It will also be obvious that instead of connecting one terminal of the secondary coil 11 of the transformer to the ground 19 it may be connected to a second bare wire supported on the posts 24 in spaced and insulated relation to the wire 21.

The circuit herein shown and described makes it unnecessary to rectify the alternating current supplied from the line because the tube 14 is itself a rectifier and supplies direct current to the fence. This effect is, of course, produced by the tube 14 which is a vacuum tube of the uni-directional type. This feature renders the device very simple and economical to construct.

It will be apparent that this invention obviates difficulties present in former fences by maintaining a substantially constant current in the fence at all times, no matter what resistance may be placed across the fence. Furthermore, the current can never rise to a value that may cause death or an exceedingly severe shock to an animal which may come in contact therewith.

The scope of the invention is indicated in the appended claims:

1. An electric fence comprising a normally open electric circuit including a source of electric current, a bare fence wire and an automatically variable impedance, said impedance including a vacuum tube of the uni-directional type comprising an anode, a cathode, and a control electrode, a connection between said anode and the source of electric current, a connection between said cathode and said bare wire, a connection between said control electrode and said cathode, said last mentioned connection including a resistance, and a connection between said source of current and a conductor normally insulated from said bare fence wire.

2. An electric fence comprising a normally open electric circuit including a source of electric current, a bare fence wire and an automatically variable impedance in series therewith, said circuit being adapted to be closed by varied resistances, said impedance including a thermionic device having an anode, a cathode and a control electrode, a connection between said source of electric current and said anode, a connection between said cathode and said fence wire, a connection between said control electrode and said cathode, said last named connection including a resistor element, a second control electrode in said thermionic device, and a connection including a resistor element between said second control electrode and said anode.

3. An electric fence comprising a normally open electric circuit including a bare fence wire and a source of electric current, a thermionic electric discharge device having an anode, a cathode, and a control electrode, a connection be-

5 tween said anode and the source of electric current, a connection between the cathode and said fence wire, a connection including an impedance between said cathode and said control electrode, and a connection between the source of current and the ground.

4. An electric fence comprising a normally open electric circuit including a bare fence wire and a source of electric current, a thermionic electric discharge device having an anode, a cathode, a control electrode and a screen grid, a connection between said anode and said source of electric current, a connection between the anode and said screen grid, said last mentioned connection including a resistor element, a connection between the cathode and said fence wire, a connection including an impedance between said

cathode and said control electrode, and a connection between the source of current and the ground.

5. The combination set forth in claim 4 wherein the resistor element located between the anode and the screen grid is a neon lamp.

6. An electric fence comprising a normally open electric circuit adapted to be closed by varied resistances and including an impedance in series therewith, said impedance including a thermionic electric discharge device having an anode, a cathode and a control electrode, said impedance being automatically variable to maintain the current flowing in the circuit, when closed, within predetermined limits.
